UNITED STATES PATENT OFFICE

151,986

DESIGN FOR A WASTE CAN

Bertis F. Hamilton, Columbus, Ind.

Application March 6, 1947, Serial No. 137,399

Term of patent 14 years

(Cl. D58—22)

To all whom it may concern:

Be it known that I, Bertis F. Hamilton, a citizen of the United States, residing at Columbus, Bartholomew County, Indiana, have invented a new, original, and ornamental Design for a Waste Can, of which the following is a specification, reference being had to the accompanying drawing, forming part thereof.

Fig. 1 is a top plan view of a waste can showing my new design;

Fig. 2 is a front elevational view thereof, and Fig. 3 is a side elevational view thereof.

I claim:

The ornamental design for a waste can, as shown.

BERTIS F. HAMILTON.
